UNITED STATES PATENT OFFICE.

ELWOOD C. PHILLIPS, OF CHICAGO, ILLINOIS.

IMPLEMENT FOR OPERATING SPRING-BUNGS.

SPECIFICATION forming part of Letters Patent No. 679,160, dated July 23, 1901.

Application filed February 25, 1901. Serial No. 48,660. (No model.)

To all whom it may concern:

Be it known that I, ELWOOD C. PHILLIPS, a citizen of the United States of America, and a resident of Chicago, in the county of Cook 5 and State of Illinois, have invented certain new and useful Improvements in Implements for Operating Spring-Bungs, of which the following is a specification.

The present invention relates to an implement for operating spring-bungs into an open or extended condition and holding the same during the operation of removal and insertion.

The object of the present invention is to provide a simple, durable, and effective implement with which the sections of a spring-bung are forced apart into an open or extended condition and so held during the insertion or removal of the bung or stopper from the barrel hole or opening, all as will hereinafter more fully appear, and be more particularly pointed out in the claims. I attain such object by the construction and arrangement of parts illustrated in the accompanying drawings, in which—

25 Figure 1 is a side elevation of a spring-bung-operating implement embodying the present invention and showing the spring-bung in section in a normally-closed condition in the barrel-opening and the implement in its initial position of engagement with the bung. Figs. 2 and 3 are fragmentary sectional elevations of the implement in its initial operative engagement with the bung and in its final position to effect an opening or extension 30 of the bung, respectively.

Similar numerals of reference indicate like parts in the different views.

Referring to the drawings, 1 represents the main section of a spring-bung carrying an elastic closure-skirt 2, 3 the movable member of the bung engaging said skirt, and 4 a spring tending to draw the two bung members together to effect an expansion of the skirt 2 against the walls of the bung-hole and a rigid 45 engagement of the spring-bung in place.

No claim is made in the present case to the above-described construction of spring-bung, as the same constitutes the subject-matter of my prior Letters Patent, No. 668,120, dated 50 February 12, 1901.

The present invention involves a pair of handles 5 and 6, pivoted together at 7 and

adapted to be drawn together by hand in an active operation of the implement. At its lower end the implement is provided with 55 laterally-expanding jaws 8 and 9, preferably pivoted together at their upper ends and having outturned lips or flanges 10, which in an expanding movement of said jaws are adapted to engage beneath the inturned flange 11 60 of the bung to connect the implement to the bung against detachment during the active use of the implement.

12 is a longitudinally-moving plunger having a central relation with the jaws 8 and 9 65 and operatively connected to the handle 6 of the pair of operating-handles by a lateral arm 13 or other equivalent connection, so as to receive positive longitudinal movement therefrom.

14 is a tapering point on the lower end of the plunger adapted to engage the lower ends of the jaws 8 and 9 and effect a positive expanding movement of the same in the initial active operation of the implement, and said 75 jaws are maintained in such expanded condition on a further operation of the implement by the width or diameter of the shank portion of the plunger, as shown.

The scope of the present invention embraces, broadly, an implement having laterally-moving jaws adapted to effect an attachment during use with a spring-bung and means moving at right angles to the movement of such jaws to effect an opening movement of the bung parts, regardless of the particular mechanism employed to accomplish such result.

In the operation of the present implement the operator inserts the implement with its 90 handles in an open condition into the outer central opening of the bung, as illustrated in Fig. 1, after which the handles are pulled together by hand. In an initial movement of such handles together the inclined or tapering point of the plunger 13 acts to spread the jaws 8 and 9 to effect an engagement of the same with the inturned flange 11 of the bung and with a continued movement of the handles 8 and 9 together and a consequent downward movement of the plunger 12. Such plunger, by its engagement against the upper end of the movable member 3 of the bung, will force the same downward away from the main 95 100

bung member or section 1 to effect an open condition of the bung. By maintaining the grasp upon the handles 5 and 6 the operator can maintain the bung parts in such open condition during a removal or insertion of the bung.

Having thus fully described my said invention, what I claim as new, and desire to secure by Letters Patent, is—

- 10 1. In an implement for operating spring-bungs, the combination of a pair of operating-handles pivoted together, a pair of jaws having outturned bung-engaging lips at their lower ends operatively connected to the handles and adapted to expand laterally with an initial closing movement of the handles, and means capable of longitudinal movement connected to the handles and adapted to be operated by the final closing movement of the handles to engage and impart movement to the movable member of the bung in a direction away from the stationary bung member in engagement with the pair of jaws, substantially as set forth.
- 15 2. In an implement for operating spring-bungs, the combination of a pair of operating-handles pivoted together, a pair of jaws having outturned bung-engaging lips at their lower ends operatively connected to the handles and adapted to expand laterally with an initial closing movement of the handles, and a longitudinally - arranged plunger operatively connected to the handles and adapted to be operated by the final closing movement

of the same to engage and impart movement 35 to the movable member of the bung in a direction away from the stationary bung member in engagement with the pair of jaws, substantially as set forth.

3. An implement for operating spring- 40 bungs, the same comprising, a pair of operating-handles pivoted together, a pair of laterally-moving jaws adapted to engage the bung, and means moving in a longitudinal direction, for engaging and forcing the bung 45 members apart, the same comprising a longitudinally-moving plunger having operative connection with a lateral arm of one of the handles, substantially as set forth.

4. An implement for operating spring- 45 bungs, the same comprising, a pair of operating-handles pivoted together, a pair of laterally-moving jaws adapted to engage the bung, and means moving in a longitudinal direction, for engaging and forcing the bung 55 members apart, the same comprising a longitudinally-moving plunger having operative connection with a lateral arm of one of the handles and provided with a tapering end adapted to effect a positive lateral movement 60 of the laterally-expanding jaws, substantially as set forth.

Signed at Chicago, Illinois, this 19th day of February, 1901.

ELWOOD C. PHILLIPS.
